UNITED STATES PATENT OFFICE

2,509,109

HANGING BRACKET FOR ILLUMINATING
TUBES

Bert C. Pretzer, St. Clair Shores, Mich., assignor
to Illuminating Engineering Company, Hazel
Park, Mich., a corporation of Michigan

Application July 5, 1949, Serial No. 103,039

7 Claims. (Cl. 240—11.4)

1

This invention relates to fluorescent lighting fixtures, and more particularly to lighting fixtures of the type which includes a central cover and a plurality of oppositely arranged U-shaped lighting tubes which project outwardly from said cover.

Heretofore in illuminating fixtures of this type it was necessary to provide a secondary supporting bracket which depended from the ceiling in order to support the outer end of each of such illuminating tubes. These were unsightly and detracted from the appearance of the lighting fixture.

It is the principal object of this invention to provide a novel adjustable tube-supporting bracket which is carried by the central fixture cover and which is adapted to supportingly engage intermediate portions of the lighting tubes.

It is the object of this invention to provide a novel bracket for said tubes which includes a cradle element adapted to support the tubes intermediate their ends with said cradle being centrally supported within the outer end portion of an adjustable bracket carried by the fixture cover or housing.

It is the further object of this invention to provide an adjustability feature in said bracket whereby the illuminating tubes may be slightly raised or lowered as desired.

These and other objects will be seen from the following specifications and claims in conjunction with the appended drawing in which:

Figure 1 is a perspective view of the lighting fixture to which applicant's tube supporting bracket is attachable.

Figure 2 is a fragmentary elevational section illustrating the method of mounting and adjustably securing said bracket to the fixture cover; and

Figure 3 is an enlarged perspective view of the tube supporting bracket with the fixture cover and a pair of tubular elements fragmentarily shown in phantom.

It will be understood that the above drawing illustrates merely a preferred embodiment of this invention and that other embodiments are contemplated within the scope of the claims hereafter set out.

Referring to the drawing, the lighting fixture includes the circularly shaped cover 11 with an annular out-turned lip 12 at its upper edge, said cover having formed in its exterior surface a plurality of circular openings 13, shown in Figure 3, from which project the ends 14 and 15 which form a U-shaped illuminating tube.

2

In the present embodiment there are four such U-shaped tubes arranged around the cover 11 at right angles to each other, there being suitable electrical connections provided on the interior of cover 11 whereby said illuminating tubes can be properly energized, with such construction forming no part of the present invention.

Referring to Figures 2 and 3, it is seen that the cover 11 has formed in its outer surface 10 between the respective tube openings 13 a pair of vertically aligned openings 16 and 17 through which the ends of the tube supporting bracket project.

More particularly said bracket consists of a 15 V-shaped support including the supporting arms 18 and 22, arm 18 terminating at its inner end, in the inturned portion 19 which projects over the top of lip 12 and extends outwardly through opening 16 formed in the cover 11.

20 Elements 18 and 22 terminate at their outer ends in the arcuate apex 20, there being a downwardly depressed portion 21 formed in element 18 adjacent apex 20 for a reason which will be apparent from the following description.

25 The inner end of arm 22 terminates in a threaded portion 23, and the latter projects inwardly through the opening 17 in cover 11 as shown in Figure 3. The knurled nut 24 threadably engages the arm 22 over its threaded portion and cooperatively bears against the exterior wall of the cover 11 as shown.

By this construction the end portion of arm 22 may be manually adjusted inwardly and outwardly with respect to cover 11.

30 35 A tube supporting cradle is provided which includes the oppositely arranged cradle elements 25 having a central upwardly formed portion 26', cradle elements 25 terminating in the tube engaging arcuate upturned members 26 which are adapted to supportably engage illuminating tubes 14 and 15 at points intermediate their ends for supporting same.

30 45 By the present construction an ornamental yet simplified tube supporting bracket is provided which is easily fastened to the cover 11 of the illuminating fixture, and a very effective and rigid tube support is provided.

The knurled nut 24 in cooperation with the threaded end 23 of arm 22 provides a means of 50 raising or lowering the apex end 20 of the arms 18 and 22 whereby the cradle 25 may be raised or lowered as desired to regulate the positioning of the tubes 14 and 15.

It will be noted that the central upturned 55 portion 26' of cradle 25 projects through the

hollow apex 20 of the bracket 18—22, and at the same time the downwardly depressed portion 21 of arm 18 tends to retain said transverse cradle element in the position shown.

Having described my invention, reference should now be had to the claims that follow for determining the scope thereof.

I claim:

1. In a lighting fixture having a central cover and a plurality of U-shaped lighting tubes horizontally projecting therefrom, a tube hanging bracket for each of said tubes comprising a formed tube supporting cradle engageable with said tubes intermediate their ends, and a transverse substantially V-shaped support extending from said cover with said cradle projected through its apex and centrally supported thereby, and with the ends of said support joined to said cover in vertically spaced relation.

2. In a lighting fixture having a central cover and a plurality of U-shaped lighting tubes horizontally projecting therefrom, a tube hanging bracket for each of said tubes comprising a formed tube supporting cradle engageable with said tubes intermediate their ends, and a transverse substantially V-shaped support extending from said cover with said cradle projected through its apex and centrally supported thereby, and with the ends of said support being in vertical alignment and joined to said cover in spaced relation.

3. In a lighting fixture having a central cover and a plurality of U-shaped lighting tubes horizontally projecting therefrom, a tube hanging bracket for each of said tubes comprising a formed tube supporting cradle engageable with said tubes intermediate their ends, and a transverse substantially V-shaped support extending from said cover between the elements of said U-shaped tubes, with said cradle projected through its apex and centrally supported thereby, and with the ends of said support joined to said cover in vertically spaced relation.

4. In a lighting fixture having a central cover and a plurality of U-shaped lighting tubes horizontally projecting therefrom, a tube hanging bracket for each of said tubes comprising a formed tube supporting cradle engageable with said tubes intermediate their ends, and a transverse substantially V-shaped support extending from said cover with said cradle projected through its apex and centrally supported thereby, there being a pair of spaced vertically aligned openings in said cover between the ends of each tube, and with the ends of said support projected through said openings respectively and joined to said cover.

5. In a lighting fixture having a central cover and a plurality of U-shaped lighting tubes horizontally projecting therefrom, a tube hanging bracket for each of said tubes comprising a formed tube supporting cradle engageable with said tubes intermediate their ends, and a transverse substantially V-shaped support horizontally extending from said cover with said cradle projected through its apex and centrally supported thereby, there being a pair of spaced vertically aligned

openings in said cover between the ends of each tube, and with the ends of said support projected through said openings respectively and joined to said cover, the upper of said ends being immovably joined to said cover, and the lower of said ends being adapted for in and out adjustments with respect to said cover.

6. In a lighting fixture having a central cover and a plurality of U-shaped lighting tubes horizontally projecting therefrom, a tube hanging bracket for each of said tubes comprising a formed tube supporting cradle engageable with said tubes intermediate their ends, and a transverse substantially V-shaped support horizontally extending from said cover with said cradle projected through its apex and centrally supported thereby, there being a pair of spaced vertically aligned openings in said cover between the ends of each tube, the ends of said support being projected through said openings respectively, the upper of said ends being arcuately formed to extend over said cover and outwardly through one of said openings, the lower of said ends being threaded and adapted for in and out adjustments through the other opening in such cover, and a manually adjustable nut on such threaded portion cooperatively engageable with the surface of said cover.

7. In a lighting fixture having a central cover and a plurality of U-shaped lighting tubes horizontally projecting therefrom, a tube hanging bracket for each of said tubes comprising a centrally upturned cradle with arcuate upturned ends engageable with said tubes intermediate their ends, and a transverse substantially V-shaped support extending horizontally from said cover, with a portion of said support adjacent its apex being depressed and with said cradle projected through said apex and centrally retained by said depressed portion, there being a pair of spaced vertically aligned openings in said cover between the corresponding ends of each tube, the ends of said support being projected through said openings respectively, the upper of said ends being immovably joined to said cover through the upper opening, the lower of said ends being projected through said lower opening and adapted for adjustment inwardly and outwardly therethrough, and a threaded nut adjustably mounted on said lower end and engageable with the surface of said cover.
